CLAIM

The ornamental design for a combined beverage can top and straw, as shown and described.

DESCRIPTION

FIG. 1 is a perspective view of a combined soda can top and straw showing my new design, the can shown in broken lines for illustrative purposes only;

FIG. 2 is a rear elevational view thereof, the front being a mirror image;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross-sectional view thereof, taken in the direction of the arrows along line 7—7 of FIG. 3.
